UNITED STATES PATENT OFFICE.

WILLIAM S. FRANKLIN, OF SOUTH BETHLEHEM, PENNSYLVANIA, ASSIGNOR
OF ONE-HALF TO JOHN HENRY KLINCK, OF CHARLESTON, SOUTH
CAROLINA.

GUNNER'S EAR-MUFFLE.

SPECIFICATION forming part of Letters Patent No. 710,572, dated October 7, 1902.

Application filed March 27, 1899. Serial No. 710,705. (No model.)

To all whom it may concern:

Be it known that I, WILLIAM S. FRANKLIN, of South Bethlehem, in the county of Northampton, and in the State of Pennsylvania, have invented certain new and useful Improvements in Ear-Muffles; and I do hereby declare that the following is a full, clear, and exact description thereof, reference being had to the accompanying drawings, in which—

10 Figure 1 is an enlarged section view of an ear-muffle embodying my invention, and Fig. 2 is a view of two such muffles mounted on a spring.

Letters of like name and kind refer to like parts in each of the figures.

The object of my invention is to provide a device by which the ear can be protected from the sound of heavy concussions or from other loud sounds without interfering with the communication of lesser sounds thereto; and to such ends my invention consists in the ear-muffle hereinafter specified.

In carrying my invention into practice I provide a casing preferably consisting of a 25 funnel-shaped part A and a cap B, the latter being secured in place over the larger end of the former by a female screw-thread in the cap which is engaged by a male screw-thread on the funnel. The cap preferably has an 30 outwardly-flaring opening in its outer end. On the larger end of the funnel and at the base of the thread in the cap are formed plane surfaces a and b, respectively, which are, in effect, opposite shoulders. A preferably imperforate diaphragm C rests against the shoulder b, and a perforated diaphragm D rests 35 against the shoulder a. A space E is formed between the diaphragms C and D, as by interposing a washer F between such parts or by dishing the diaphragm D. The diaphragms 40 C and D, or at least the former, are preferably firmly clamped between the shoulders a and b. The diaphragm C is so formed as to be capable of vibrating under the action of 45 sound-waves. It may be formed of sheet metal and is made thin enough to give it the desired sensitiveness to sound-waves. The diaphragm D, however, is so formed as to be practically unresponsive to the vibrations of 50 sound-waves. The distance between the dia-

phragms is such that while the diaphragm C can vibrate freely in response to sound-waves of ordinary intensity it will come into contact with the diaphragm D when waves of more than the desired intensity occur. The 55 latter diaphragm, being stiff and incapable of vibration, holds the former diaphragm and prevents it from transmitting the sound-waves beyond the desired intensity to the air within the funnel, and hence prevents their 60 transmission to the ear. It also prevents the breakage of the diaphragm C under the action of violent sound-waves. I have found by practical experiment that with the proper adjustment of the diaphragms the sound of 65 the firing of cannon is prevented from reaching the ear, while ordinary conversation can be heard practically as well as usual. The advantage of such result is obvious when it is remembered that the drum of the ear is 70 often severely injured and even broken by such sounds as the concussions of large guns.

It is desirable to use two of my ear-muffles at the same time, and hence I mount two of them on a spring G, which is curved to pass 75 over or behind the head. The ends of the spring are formed into or attached to eyes g and g', which are adapted to be passed over the smaller ends of the funnels and to be locked against shoulders a' and a' thereon by 80 nuts a² and a²', which engage screw-threads at the base of such ends. The smaller ends of the funnels are preferably of such size as to be readily received into and to completely 85 fill the external orifices of the ears.

In operation the smaller ends of the funnels are introduced into the external orifices of the ears, so that no sounds can enter the ears except through the funnels. When sounds occur, their waves enter the opening in the cap 90 and strike the diaphragm C, causing it to vibrate. If such sounds are below the intensity the transmission of which it is desired to prevent, the diaphragm in its vibration does not strike the diaphragm D, and hence the 95 sound is perfectly transmitted to the air within the funnel and by this medium reaches the ear. If, however, the sounds are such that the diaphragm C vibrates beyond the normal amplitude, the latter strikes against 100

the diaphragm D and is prevented from communicating such impulse to the air within the funnel as to distress the ear.

It is obvious that changes can be made in 5 the above-described construction that are within the scope of my invention. For instance, the casing can be made of such a shape as to inclose the whole ear instead of being received into the ear. The diaphragm 10 C can be either simple or compound, or it can be made thicker toward the edges than in the center. Wire-netting or a strip of metal can be used in place of the perforated diaphragm D. When the diaphragm C is clamped between the shoulders a and b, it can only 15 vibrate until its fibers are stretched taut, and it will hence be unable to transmit sounds beyond a given loudness or amplitude of vibration. The same effect is produced by a 20 diaphragm that is thinned toward the center, even if such diaphragm is not clamped. In such cases the diaphragm D may serve only to prevent breakage of the diaphragm C and can be omitted if it is not needed for such 25 purpose.

Having thus described my invention, what I claim is—

1. An ear-muffle consisting of the combination of a diaphragm and a stop to limit the 30 amplitude of vibration of the diaphragm, substantially as and for the purpose described.
2. An ear-muffle consisting of the combination with a chamber adapted to be placed in communication with the ear, of a diaphragm 35 in a wall of such chamber whose vibrations

are limited to a predetermined amplitude, whereby sounds below a certain intensity are transmitted to and sounds of greater intensity are prevented from, reaching the ear, substantially as described.

3. An ear-muffle consisting of the combination with a chamber adapted to be placed in communication with the ear, of a diaphragm 40 in a wall of such chamber, and an abutment against which said diaphragm is adapted to strike when vibrated beyond a predetermined amplitude, substantially as described.

4. An ear-muffle consisting of the combination with a chamber adapted to be placed in communication with the ear, of a diaphragm 45 in a wall of such chamber, and an abutment situated within said chamber and against which such diaphragm is adapted to strike when vibrated beyond a predetermined amplitude, substantially as described.

5. An ear-muffle consisting of the combination with a chamber adapted to be placed in communication with the ear, of a diaphragm 50 in a wall of such chamber, and an abutment consisting of a perforated non-vibrating wall 55 adjacent to but normally not touching said diaphragm, substantially as described.

In testimony that I claim the foregoing as my invention I have signed my name in presence of two subscribing witnesses.

—WILLIAM S. FRANKLIN.
